Application September 17, 1948, Serial No. 148,626

Term of patent 14 years

(Cl. D61—1)

To all whom it may concern:

Be it known that we, Harris E. Nelson and Frank Lustig, citizens of the United States, residing at Chicago, in the county of Cook and State of Illinois, have invented a new, original, and ornamental Design for a Movie Projector Carrying Case, of which the following is a specification, reference being had to the accompanying drawing, forming a part thereof, in which:

Fig. 1 is an end elevational view of a movie projector carrying case showing our new design;

Fig. 2 is a side elevational view thereof;

Fig. 3 is an end elevational view of the opposite end to that shown in Fig. 1, and

Fig. 4 is a top view thereof.

We claim:

The ornamental design for a movie projector carrying case, as shown.

HARRIS E. NELSON.
FRANK LUSTIG.
